UNITED STATES PATENT OFFICE.

RAYMOND N. EHRHART, OF JEANNETTE, PENNSYLVANIA, ASSIGNOR TO WESTINGHOUSE ELECTRIC & MANUFACTURING CO., A CORPORATION OF PENNSYLVANIA.

STEAM-ACTUATED EJECTOR.

Application filed September 21, 1917, Serial No. 192,503. Renewed July 22, 1922. Serial No. 576,870.

To all whom it may concern:

Be it known that I, RAYMOND N. EHRHART, a citizen of the United States, and a resident of Jeannette, in the county of Allegheny and 5 State of Pennsylvania, have made a new and useful Invention in Steam-Actuated Ejectors, of which the following is a specification.

This invention relates to steam actuated ejectors and has for an object to produce an 10 ejector capable of being employed as an air ejector for condensers or other apparatus in which a high vacuum is to be maintained.

A further object is to produce an ejector which is more effective and has a greater air 15 handling capacity per unit of weight and space occupied than other ejectors now in use and known to me.

A further object is to produce an improved 20 fluid actuated air ejector which is simpler in details of construction and is simpler to manufacture than similar ejectors now in use and known to me.

These and other objects are attained by 25 means of an ejector embodying the features herein described and illustrated.

In the drawings: Fig. 1 is a diagrammatic view of a well known form of steam actuated air ejector.

Fig. 2 is a diagrammatic sectional view of 30 a diffuser forming a part of an ejector similar to that illustrated in Fig. 1.

Fig. 3 is a diagrammatic view of a number of diffusers which, in aggregate, have 35 the same capacity and the same compression ratio as the diffuser of Fig. 2.

Fig. 4 is a diagrammatic sectional view of an ejector embodying my invention.

Figs. 5, 6 and 7 are transverse sections 40 through the diffuser 16 taken respectively on the lines 5—5, 6—6 and 7—7 of Fig. 4.

Steam actuated ejectors capable of withdrawing air from steam condensers or containers in which a high vacuum is maintained, must be so designed that the various 45 fluid passages are properly proportioned with relation to each other in order to provide an ejector which is capable of starting and is capable of maintaining the desired vacuum with sufficient economy to be 50 commercially practical.

Leblanc Patents Nos. 1,175,461 and 1,215-, 321 of March 14, 1916 and February 6, 1917 respectively set forth ejectors capable for use as air pumps for steam condensers and 55 disclose in part the difficulties encountered

by ordinary ejectors and overcome by the Leblanc ejector inventions.

My present invention has for its object to produce an air ejector capable of accomplishing the results attained by the Leblanc 60 ejector, but which is more compact and consequently better adapted for commercial use where ejectors of relatively large capacity are necessary.

In Fig. 1, I have diagrammatically illustrated a Leblanc ejector for the purpose of comparing it with the ejector of the same or greater capacity, illustrated in Fig. 4 as an embodiment of my invention. The ejector of Fig. 1 includes a ring of nozzles 8, 70 capable of discharging motive fluid into and through a diffuser 7, which communicates directly with an air inlet port 6. The outlet of the diffuser 7 discharges into a second convergent divergent diffuser 9, the 75 discharge of which communicates with the atmosphere. A series of nozzles 11 discharges into and through the diffuser 9. The nozzles 8 converge so that the stream of steam discharged from them conforms more 80 to less closely to the contour of the converging portion of the diffuser 7. The nozzles 11 are similarly inclined so that the steam issuing from them moves in a path which is substantially parallel to the adjacent walls of the tube 9. In order to obtain 85 an efficient and at the same time an effective ejector, it is necessary to proportion the throat areas of the diffusers to the outlet areas in such a way that the desired pressure conversion is accomplished in each diffuser. Inasmuch as the angle of divergence of the diffusers must be carefully determined 90 in order to accomplish the desired result and therefore must be more or less constant 95 in diffusers designed to accomplish the same degree of compression, it will be apparent that ejectors designed to pass large volumes of steam and air will of necessity be relatively long and that the increase in 100 length will necessitate an increase in thickness of material and consequently the amount of material used. When it is considered that the ejector should be operated in a vertical position, it will be apparent that 105 for large sizes the ejector is not only ungainly and expensive on account of size, but will necessitate a relatively large amount of head room. The question of head room alone is an item where the ejector is em- 110

ployed as a part of a marine installation and consequently a reduction in length is often as important as a reduction in weight.

In Fig. 2, I have illustrated a diffuser 5 which has, for example, a 6° angle from the smallest portion or throat to the largest portion or outlet.

In Fig. 3, I have illustrated four smaller diffusers having in total the same throat 10 area and outlet area as the diffuser of Fig. 2 and each having the same angle of divergence. It will, therefore, be apparent that if the four diffusers of Fig. 3 are grouped together their length will be much 15 less than that of the diffuser of Fig. 1, whereas they will be capable of accomplishing the same results as could be accomplished by the diffuser of Fig. 2.

In Fig. 4, I have embodied this idea in 20 an ejector, but instead of employing separate diffusers of reduced cross section, I have replaced the relatively long diffusers 25 of the Leblanc ejector by relatively short annular diffusers 14 and 16 having passages 14' and 16'. The diffuser 14 may be considered as having the same throat area and outlet area as the diffuser 7 and its angle of divergence may also be considered as that of the diffuser 7. The same comparison 30 may be made between the diffuser 16 and the diffuser 9. Another advantage gained by the arrangement of diffusers illustrated in Fig. 4 is that the motive fluid delivery 35 nozzles, cooperating with the diffusers, may extend axially of the ejector and in this way simplify the operation of machining the entire ejector. In addition to this, the 40 series of nozzles 8 of the Leblanc ejector may be well replaced by one annular nozzle 45 17, which is axially aligned with the annular diffuser 14 and so arranged as to discharge the stream of steam issuing from it 50 axially with relation to the annular passage through the diffuser. The same is true of 55 the means for delivering motive fluid to the second diffuser 16, and in the drawings I have illustrated a single annular nozzle 60 20 axially arranged with relation to the annular diffuser 16 and so located as to 65 deliver an annular stream of motive fluid into and through the annular diffuser. As 70 illustrated, the nozzle 17 receives motive fluid from a steam chest 18, and the nozzle 20 receives motive fluid from an annular 75 steam chest 22, so arranged as to provide a minimum amount of resistance to the fluid issuing from the diffuser 14 and entering the diffuser 16. Both nozzles 17 and 20 are 80 divergent nozzles, each being designed to 85 expand the motive fluid traversing it to substantially the pressure normally existing at the outlet end of the nozzle.

The air intake to the ejector is illustrated 90 at 15 and the atmospheric exhaust port is 95 shown at 21. It will, of course, be apparent

100 that the annular nozzle 17 may be replaced by a group of nozzles arranged in an annular series, or by nozzles of different angles and arranged in different rows. The same is true of the nozzle 20, although 105 I prefer to employ a single annular nozzle for delivering steam to the second diffuser tube.

In Fig. 5, I have illustrated the arrangement of the webs 24 employed for holding 110 the central wall 24' of the annular diffuser 16 in place. A similar arrangement of webs 115 may be employed in connection with the diffuser 14 and if necessary the steam chamber 22 may be supported by webs. Figs. 6 120 and 7 illustrate respectively the annular nozzle 20 and the annular diffuser 16.

While I have illustrated and described 125 but one embodiment of my invention, it will be apparent to those skilled in the art 130 that various changes, modifications, additions and omissions may be made in the apparatus illustrated without departing 135 from the spirit and scope of the invention, as set forth by the appended claims. 140

What I claim is:

1. In combination in a steam actuated air 145 ejecting device, a diffuser communicating with a source of fluid to be ejected, a motive 150 fluid delivery nozzle for discharging a stream of motive fluid into and through said 155 diffuser, an annular diffuser arranged substantially in the same direction as the first 160 mentioned diffuser and communicating with the outlet of the latter, and annular divergent 165 nozzle structure for expanding and delivering motive fluid into and through said 170 annular diffuser. 100

2. In a steam operated air ejector, a substantially annular convergent-divergent diffuser 180 communicating with a receptacle to be evacuated, divergent annular nozzle structure for expanding motive fluid and for delivering it into said diffuser, a second diffuser 185 communicating with the outlet of the first diffuser, and annular divergent nozzle structure located between said diffusers for 190 expanding motive fluid and for delivering the fluid so expanded into the second diffuser. 110

3. An air ejector comprising the combination of a first substantially annular convergent-divergent diffuser, annularly arranged divergent nozzle structure for discharging motive fluid into the diffuser, a second substantially annular convergent-divergent diffuser 200 communicating with the first diffuser, and annularly arranged divergent nozzle structure arranged between the diffusers and adapted to discharge motive fluid into the second diffuser. 115

4. An air ejector comprising a substantially annular convergent-divergent diffuser 210 adapted to communicate with a source of air to be withdrawn and substantially an- 120

- 5 nular divergent nozzle structure adapted to discharge motive fluid into the diffuser, the axes of the diffuser and nozzle structure extending in the same direction and in the direction of flow of motive fluid and air. 45
- 5 An air ejector comprising a convergent-divergent diffuser constructed with cross-sections of the fluid passage therethrough each defining a substantially annular area, in combination with divergent fluid expanding nozzle structure which corresponds in shape and position with said diffuser so as to effectively deliver actuating fluid therethrough. 10
- 10 6. In a fluid translating device, the combination of a substantially annular diffuser and divergent expansion nozzle structure for expanding and discharging motive fluid at high velocity into the annular diffuser, the axes of the nozzle and the diffuser extending in the same direction and in the direction of flow of motive fluid. 15
- 15 7. A fluid translating device comprising a longitudinally extending annular convergent-divergent diffuser, an inlet chamber communicating with the converging portion of the diffuser, and annular divergent expansion nozzle structure having its axis substantially coincident with the axis of the diffuser for discharging motive fluid through at least a part of the inlet chamber and into the converging portion of the diffuser. 20
- 20 8. In a two-stage ejector, the combination of a longitudinally extending annular convergent-divergent diffuser adapted to communicate with a source of air to be withdrawn, annularly arranged divergent nozzle structure for discharging motive fluid through the diffuser, a second longitudinally extending annular convergent-divergent diffuser in communication with the first diffuser, and a second annularly arranged divergent nozzle structure arranged between 25
- 25 the diffusers and adapted to discharge motive fluid through the second diffuser. 45
9. In an ejector, the combination of an annular convergent-divergent diffuser adapted to communicate with a source of air to be withdrawn, annularly arranged divergent nozzle structure adapted to expansively discharge motive fluid at high velocity through the diffuser, a convergent-divergent diffuser in communication with the first diffuser, and divergent nozzle structure adapted to expansively discharge motive 50 fluid at high velocity through the second diffuser, the axes of the first and second nozzle structures and the diffusers extending in the same direction and in the direction of flow of motive fluid and air. 55
10. In an ejector, the combination of a substantially annular convergent-divergent diffuser adapted to communicate with a source of medium to be withdrawn, substantially annularly arranged divergent 60 nozzle structure adapted to expansively discharge motive fluid at high velocity through the diffuser, a second substantially annular convergent-divergent diffuser in communication with the first diffuser, a substantially annular 65 motive fluid chest arranged between the diffusers, substantially annular divergent nozzle structure in communication with the chest and adapted to expansively discharge motive fluid therefrom at high velocity through the second diffuser, the discharge from the first diffuser adapted to flow through and about the chest and the nozzle communicating therewith. 70
- 75 In testimony whereof, I have hereunto 80 subscribed my name this 20th day of September, 1917.

RAYMOND N. EHRHART.

Witness:

C. W. McGHEE.
